(57) **CLAIM**

The ornamental design for a wind deflector for motorcycle fairing, as shown and described.

DESCRIPTION

The nature and intended use of the article in which the design is embodied is for a wind deflector which may be mounted to the fairing of a motorcycle immediately above the headlight of the motorcycle.

FIG. 1 is a perspective view of a motorcycle equipped with the wind deflector for motorcycle fairing according to my new design.

FIG. 2 is a front left perspective view of the wind deflector for motorcycle fairing according to my new design;

FIG. 3 is front elevation view thereof;

FIG. 4 is rear elevation view thereof;

FIG. 5 is a left side view thereof;

FIG. 6 is a right side view thereof;

FIG. 7 is a top view thereof; and,

FIG. 8 is a bottom view thereof.

The portions of the drawing shown in dashed lines are for contextual purposes and form no part of the new design.
